OVERCAP FOR A PRESSURIZED CONTAINER

Herbert R. Carpenter, Kenilworth, Ill., assignor to Sequist Valve Company, Division of Pittway Corporation, Cary, Ill.

Filed July 24, 1970, Ser. No. 24,123

Term of patent 14 years

Int. Cl. D9—07

U.S. Cl. D9—258

FIG. 1

FIG. 2

FIG. 3

FIG. 4

FIG. 5

FIG. 6

FIG. 1 is a perspective view of an overcap for a pressurized container showing my new design;

FIG. 2 is a top plan view;

FIG. 3 is a bottom plan view;

FIG. 4 is a front elevational view;

FIG. 5 is a side elevational view; and

FIG. 6 is a rear elevational view thereof.

I claim:

The ornamental design for an overcap for a pressurized container, as shown.
